**COMBINED FAN AND MOUNTING BRACKET FOR
COOLING ELECTRONIC EQUIPMENT AND THE
LIKE**

Lloyd R. Bowen, 3968 Waterhouse Road, Oakland, Calif.

Filed Aug. 9, 1962, Ser. No. 71,230

Term of patent 14 years

(Cl. D62—4)

F i g. 1

F i g. 2

F i g. 3

FIGURE 1 is a perspective view of a combined fan and mounting bracket for cooling electronic equipment and the like showing my new design.

FIGURE 2 is a side view of the combined fan and mounting bracket for cooling electronic equipment and the like.

FIGURE 3 is a front view of the combined fan and mounting bracket for cooling electronic equipment and the like.

The characteristic feature of my design resides in the configuration of the mounting plate.

I claim:

The ornamental design for a combined fan and mounting bracket for cooling electronic equipment and the like, substantially as shown and described.
